ELECTRIC CIRCUIT BREAKER

Benjamin E. Getchell, Plainville, Conn., assignor
to General Electric Company, a corporation of
New York

Application August 7, 1951, Serial No. 240,688

7 Claims. (Cl. 200—166)

1

The main object of this invention is to provide a circuit breaker of compact but effective construction in which the mechanism is manually operable to open and close a circuit and which automatically opens the circuit upon an overload in the circuit.

Another object is to provide a circuit breaker of the snap-acting type which is small and compact, but in which a comparatively great separation of contacts is possible.

Another object is to provide a circuit breaker which can successfully interrupt relatively large electric currents and especially direct currents.

Another object is to provide a circuit breaker in which the moving parts pivot on a metal frame member without the use of separate pivot pins.

Another object is to provide a circuit breaker having its handle biased to seal against the cover so as to prevent the escape of hot gases or flame.

Fig. 1 is a side view and partial section of the circuit breaker showing the parts in the normal open circuit position.

Fig. 2 is a similar view but showing the parts in the closed position.

Fig. 3 is a similar view showing the parts in the automatically tripped position.

Fig. 4 is a perspective view of the circuit breaker.

Fig. 5 is a fragmentary detail view showing the support for the finger lever.

Fig. 6 is a side view of the bridge or supporting member.

Fig. 7 is an edge view of the same.

Fig. 8 is a side view of the tripping element.

Fig. 9 is an edge view of the same.

Fig. 10 is a side view of the movable switch contact member.

Fig. 11 is an edge view of the same.

Fig. 12 is a side view of the rocker member.

Fig. 13 is an edge view of the same.

Fig. 14 is a perspective view of the terminal and bimetal unit viewed from the outer edge.

Fig. 15 is a similar view of the unit seen from the inner face.

The mechanism is enclosed in an insulating housing consisting of a body part 8 which supports the mechanism and a removable part 9 which serves as a cover plate. The parts are held together by suitable fastening members such as screws or rivets 10, 10. A face plate 11 extends across the outer edge or end of the housing and provides screw seats 11'. A movable finger piece or actuating lever 12 extends outwardly from the face plate for manual operation of the circuit breaker.

2

Circuit terminals 14 and 15 are set into opposite ends of the body part of the housing. A stationary contact 16 is connected to the terminal 15 and a movable switch or contact member 17 is connected to the thermally responsive, current responsive, or bimetal strip 18 by a flexible conductor 19, and the strip is connected to the terminal 14. The bimetal strip is carried by the arm 18x and may be adjusted by a screw 18' which is adjustable in arm 18''. The part 18'' extends laterally from the upper end of arm 14' which is formed integrally with the terminal 14. This unit is mounted in a recess in the housing and may have projecting pins 14'', 14'' located in recesses in the body to assist in holding the unit in place.

A main supporting or bridge member 20 is supported at its opposite ends in the body of the housing. This member has two sides connected 20 by cross walls 20', 20''.

The tripping member 21 also has two sides, each of which is provided with a lug 22 at one end which projects outwardly into a bearing notch 22' in the bridge member 20 and has a 25 cross wall 21'. The nose 23 carried by the cross wall 21' normally rests upon the tip of the bimetal strip 18. The switch member 17 is hinged to the trip member 21 and for that purpose has a notch or bearing 24 at each side receiving the lug 24' which extends inwardly from the opposite site end of the adjacent side wall of the trip member 21.

The rocker 25 has opposed notched 26, 26' which provide bearings for the opposed lugs 26', 26' which project outwardly from the sides of 35 the bridge 20. This rocker has an integral arm 27 connected to it by a cross wall 28. A spring 30 is anchored at one end to the pin 31 on the arm 27 and is connected at 17' at its other end to the movable switch member 17. This spring 30 biases the switch member 17 against the stop 32 on the wall 20' of the bridge 20.

The operating finger piece 12 is connected to its insulating hub 33 on the rock shaft 34 supported between body 8 and cover 9. A helical spring 34a surrounds the shaft 34 and serves to bias the hub 33 upwardly into engagement with flange or socket 11'' on the face plate 11.

As shown in Fig. 5, the helical spring 34a has its opposite ends extending respectively into cylindrical recesses 34b and 34c in the opposite inner walls of the housing parts 8 and 9. Likewise, the ends of the rock shaft 34 extend into these recesses, the rock shaft having a diameter considerably smaller than the inside diameter 55 of the spring, with the end portions of the rock

shaft in the recesses resting on the end turns of the helical spring. By reason of its transverse resiliency, the spring applies a biasing force in an upward direction, as seen in Fig. 5, to the hub thereby holding the spherical portion 33a of the hub seated in the complementary outwardly arched spherical flange 11' on the base or end plate 11 around the periphery of the aperture for the finger piece 12. It will be understood that the rock shaft serves to limit the downward movement of the hub in the event that it is pushed downward with a force greater than the bias of the spring. The transverse aperture 34d in the hub through which the spring extends has a diameter at its middle substantially the same as the recesses and slightly greater than the outside diameter of the spring, and gradually increases in diameter from the middle toward each end so that the middle wall of the aperture engages the spring to make effective the maximum transverse resiliency of the spring.

A bearing 35 which connects the two sides of the rocker 25 extends into a slot 35' in the hub 33 for moving the rocker.

The spring 38 when the arm 27 is in lower position, pulls the movable switch member 17 into closed circuit position as shown in Fig. 2, and when the arm 27 is in upper position the spring pulls the switch member to the open circuit position as shown in Fig. 1.

When in closed circuit position, the part 28 abuts against the body of the housing at 28'.

To manually open the circuit, the lever 12 is moved to the left from the position of Fig. 2 to the position of Fig. 1. This turns the rocker 25 about pivots 26' in a clockwise direction and carries the anchor end of the spring 38 above the pivot lugs 24' and throws the switch member 17 to the "off" or open circuit position. In this position, the wall 28 abuts against the bridge member 20.

To close the circuit after manual opening, the lever 12 is manually moved to the right from the position of Fig. 1 to the position of Fig. 2 thereby turning the rocker 25 anticlockwise about its pivots 26'. This moves the arm 21 downwardly carrying the anchored end of the spring 38 below the bearings 24' so that the spring turns the movable switch contact 11 around said bearings 24' and snaps it into closed position against the stationary contact 10.

When the circuit is closed and an overload in the circuit warps the bimetal strip 18, the nose 23 of the tripping member 21 is released and the spring 38, acting through the switch member 17, applies pressure against the pivot bearings 24' of the tripping member 21, turns the tripping member about the bearings 22, and throws the trip member into the position of Fig. 3 thereby carrying the switch member 17 to "off" position.

To reset the switch mechanism, after being tripped to the open position of Fig. 3, the lever 12 is manually moved to the left thereby turning rocker 25 clockwise on pivots 26'. The wall 23 then engages the lower edge of the trip member 21, and turns it clockwise about the pivots 22. This forces the nose 23 to travel up the bimetal strip 18 until it latches on to the tip of the bimetal as shown in Fig. 1.

I claim:

1. In a circuit breaker, a housing having an insulating body, a metal face plate secured to the body, said plate having an opening with an outwardly arched, peripheral flange provided with a seat, an actuating finger piece having a

hub with a transverse opening therein, a transverse bearing pin for said hub extending through said hub opening and supported loosely in the body, and a helical spring on said pin pressing said hub to the seat in said flange.

2. In a circuit breaker, a housing having an insulating body, a metal face plate secured to the body, said plate having an opening with an outwardly arched flange forming a seat, an actuating finger piece having a hub with a transverse opening therein, a transverse bearing pin for said hub extending through said hub opening and supported loosely in the body, and a helical spring of larger diameter than said pin on said pin pressing said hub to said seat within said flange.

3. In a circuit breaker, a housing having spaced side walls and an end wall provided with an opening, switch means mounted in said housing, a manually operated lever for said switch means projecting from said opening including a hub in said housing having a transverse aperture, closure means for said opening carried by said lever, and a helical spring extending through said transverse aperture having its ends secured to said side walls so as to bias said lever to a position closing said opening.

4. In a circuit breaker, a housing having spaced side walls provided with opposite cylindrical recesses and an end wall provided with an opening, switch means mounted in said housing, a manually operated lever for said switch means projecting from said opening including a hub in said housing having a transverse aperture extending between said recesses, closure means for said opening carried by said lever, and a helical spring extending through said transverse aperture having its ends extending into said recesses so as to bias said lever to a position closing said opening.

5. In a circuit breaker, a housing having spaced walls provided with opposite cylindrical recesses and an end wall provided with an opening, switch means mounted in said housing, a manually operated lever for said switch means projecting from said opening including a hub in said housing having a transverse aperture extending between said recesses, closure means for said opening carried by said lever, a helical spring extending through said transverse aperture having its ends extending into said recesses so as to bias said lever to a position closing said opening, and a bearing pin having a diameter substantially smaller than the inside diameter of said spring extending through said spring and having its ends extending into said recesses for limiting the movement of said lever relative to said end wall.

6. In a circuit breaker, a housing having spaced walls provided with opposite cylindrical recesses and an end wall provided with an opening, a spherical flange on said end wall around said opening, switch means mounted in said housing, a manually operated lever for said switch means projecting from said opening including a hub in said housing having a surface fitting into said flange and a transverse aperture extending between said recesses, said transverse aperture having substantially the same diameter at its middle as said recesses but gradually increasing in diameter from the middle toward each end, and a helical spring extending through said transverse aperture having its ends extending into said recesses so as to bias said hub against said flange.

7. In a circuit breaker, a housing having spaced walls provided with opposite cylindrical recesses and an end wall provided with an opening, a spherical flange on said end wall around said opening, switch means mounted in said housing, a manually operated lever for said switch means projecting from said opening including a hub in said housing having a spherical surface fitting into said flange and a transverse aperture extending between said recesses, said transverse aperture having substantially the same diameter at its middle as said recesses but increasing in diameter from the middle toward each end, a helical spring extending through said transverse aperture having its ends extending into said recesses so as to bias said hub against said flange, and a bearing pin having a diameter substantially smaller than the inside diameter of said spring extending through said spring

5

and having its ends extending into said recesses for limiting the movement of said hub away from said flange.
